LIQUID DISPENSING MEANS AND STOVE
INCORPORATING SAMEMarc Resek, Cleveland Heights, Ohio, assignor to
Perfection Stove Company, Cleveland, Ohio, a
corporation of Ohio

Application April 26, 1940, Serial No. 331,850

23 Claims. (Cl. 126—93)

This invention relates to liquid dispensing apparatus, and more particularly to liquid fuel stoves or heaters incorporating such apparatus.

The present invention is based on the same principle as that which characterizes the joint invention of myself and John A. Dahlstrom, set forth in our co-pending application Serial No. 305,506, filed November 21, 1939. The principle to which reference is made is present where a reservoir, having an opening, is placed on a support with said opening in an elevated position and moved in an approximately horizontal direction, with a progressive end-over-end action, to an inverted position over a distributing receptacle or basin with said opening in discharging relation thereto.

A purpose of the present invention is to reduce the distance traveled by the reservoir in the accomplishment of a substantially complete inversion; and another object is to render positive the traction between the bearing portion of the movable structure comprising the reservoir and the element or support along which it moves.

Among the more general objects of the invention are simplicity and compactness of construction and convenience of use, all of which will more fully appear from the following description taken in conjunction with the accompanying drawings wherein Fig. 1 is a side elevation of a liquid fuel heating stove incorporating the invention with a part of the stove casing broken away and other parts shown in section; Fig. 2 is a fragmentary plan view, partly in section; Fig. 3 is a perspective view of the reservoir; Fig. 4 is a sectional rear elevation of the stove, the plane of section being indicated by the line 4—4 of Fig. 1; Fig. 5 is a similar view of the stove showing the door to the reservoir compartment swung down to open position with the reservoir resting thereon in upright position, the reservoir being indicated in inverted operative position by dot-and-dash lines, and Fig. 6 is a perspective view of one of the supporting elements or rails on which the reservoir is moved between its substantially upright position and its inverted operative position.

The stove casing 1, equipped with a closure 2 at the front, encloses a combustion chamber 3 having an annular bottom wall 4, below and in spaced relation to which is supported a burner bowl or firepot 5, such constituting the burner proper. To the rear of the casing 1 is a housing 10 that encloses a reservoir compartment at the bottom of which is located a distributing receptacle or fuel basin 12. Extending horizontally across the top of the basin is a removable plate

15 having a depressed central portion 16 whose peripheral wall is provided with screened openings 17. The distributing receptacle or fuel basin 12 communicates with the burner bowl or firepot through a conduit 20, including a metering valve 21, the operating handle 22 of which is disposed above the top of the housing 10. A flexible element (not shown) for cleaning the conduit 20 is connected to the lower end of a rod 23 that extends downwardly through a central aperture of the handle 22 and through the hollow valve stem to which the handle is attached, and is normally held in retracted position by a spring 24 that is confined between the top of the handle 22 and an abutment 25 on the rod 23. The foregoing structure constitutes no part of my present invention excepting in a general way in certain combinations, and further details of a stove of the same character may be had by reference to Patent No. 1,987,179, dated January 8, 1935.

As will appear from Figs. 2, 4 and 5, the housing 10 is open at one side, and hingedly supported in closing relation thereto is a door 30. The door is desirably hinged adjacent its lower edge to the housing through the medium of a pintle 31; and it is urged toward and held in closed position by suitable spring means, as by a tension spring 33 that has one end anchored to a part 34 adjacent the closed side of the housing and its other end connected, through a link 35, with a part 36 on the door. An ear 37 extends from the free edge of the door and serves as a stop to limit the movement of the door in closing direction by contact with the adjacent edge of the housing and also as a convenient finger piece for swinging the door downwardly to open position, as shown in Fig. 5, in which position it is stopped by the engagement of ears on side plates 38 with stops 39 that are carried by and are immovable with respect to the housing 10, said stops, as will presently appear, being directly connected to the supporting elements or rails along which the reservoir is moved between operative and inoperative positions. The weight of the door is sufficient to hold it open in opposition to the power of the spring 33 when the door is at or near the lower limit of its movement.

Suitably secured, as by fastening means 45, to the inner sides of the front and rear walls of the housing 10, are supporting elements or rails 46, one of which is shown in perspective in Fig. 6. Each includes a wall engaging portion or plate 47, laterally from the upper edge of which extends for a greater part of the length of the

element a track 48 having spaced rectangular openings 49; and beyond the inner end of the track is a depressed laterally extending seat 50. Welded or otherwise secured to the end of the portion 47 remote from the seat 50 is one of the previously mentioned stops 39. The track 48 is in the nature of a rack by reason of the openings 49.

The reservoir 55, shown in perspective in Fig. 3, is, in the present instance, generally cylindrical in shape, its peripheral wall being designated 56. According to the present construction, one of the end walls is formed integral with the peripheral wall while the other, designated 58, is seamed to the edge of the peripheral wall. Both end walls are provided with central bosses 59 that may be likened unto trunnions. They are shown in the present embodiment as cylindrical and as having suitably attached to their outer ends, as by welding or brazing, plates 60. These plates are generally circular and are provided at diametrically opposite portions with series of lugs or teeth 61, and on one side, between the two series of teeth, with what may be termed a foot 62. It will be observed that the foot 62 of each plate 60 is in approximate radial alignment with a filling and discharge opening in the peripheral wall of the reservoir that is surrounded by a threaded neck 64 to which is applied a screw cap 65, and said cap is equipped with the usual valve 66 with which is associated in the customary way a spring 67 that tends to hold the valve closed. The neck 64 that surrounds said filling and discharge opening is set within a depression 68 that serves to retain any liquid that may drip from the neck or cap when the reservoir is moved from inverted to upright position. The side of the reservoir opposite the filling opening is shown as flattened and as having applied thereto a base 69. Handles 70 are secured, as by rivets 71, to the peripheral wall 56 on opposite sides of the filling and discharge opening, and to accommodate the fingers of the person handling the reservoir, the peripheral wall is formed with depressions 72 under the handles. It may be explained while on the subject of the reservoir that except for manufacturing expediency, the lugs or teeth 61 and the feet 62 might be made integral parts of the bosses 59, or might be applied to the peripheral portions thereof as units. Because of the obvious character of such alternatives, illustration thereof is deemed unnecessary.

To replenish the oil supply of the stove, the door 30, grasped by the lug 31, is swung downwardly to the position shown in Fig. 5 where it is stopped by the engagement of the lugs on the plates 38 with the stops 39. The person attending the stove reaches into the housing 10 through the open side thereof and draws the reservoir outwardly, as by means of the near handle 70, until the feet 62, sliding on the seats 50, engage the inner ends of the tracks 46. The operator may then take hold of the reservoir and roll it out through the open side of the housing with the arcuate bearing portions of the plates 60 traversing the tracks 48, the lugs or teeth 61 entering the openings 49 to render positive the traction between the bearing parts and tracks, as in the manner of a rack and pinion. As the reservoir moves along the tracks 48, it is positively turned over so that by the time the bearing portions run off of the outer ends of the tracks, the reservoir will be deposited in substantially upright position on the door 30, the

base 69 of the reservoir resting upon elevated ribs or glides 75. The reservoir may then be shifted along the door to a more convenient position for lifting, as to the position shown in full lines in Fig. 5. The reservoir may now be carried away by means of the handles 70 and refilled, and it, or a previously filled reservoir, may be placed upon the door and pushed inwardly until stopped by engagement of one end of the base 69 with the hinged pintle 31. This disposes the reservoir in a position from which it may be swung over to bring the curved bearing edges of the plates 60 into contact with the tracks 48 after which further lateral pressure on the reservoir will cause it to roll over into inverted position with its opening in discharging relation to the distributing receptacle or basin 12; the lugs or teeth 61 again cooperating with the tracks in the manner above explained so as to insure a properly inverted position of the reservoir and a disposition of the feet 62 upon the seats 50. As the reservoir assumes this position, the valve that controls the discharge opening is unseated by contact of the outer end of its stem with the bottom of the depressed portion 16 of the plate 15. Liquid will then flow into the reservoir until the level rises sufficiently to seal the opening by contact with the cap 65. A liquid level is thus established which will prevail throughout the system including the burner bowl or firepot 5, any variation in the oil level during operation of the burner being due to the consumption of the fuel. After the reservoir is in place, the outer end of the door 30 may be lifted and the spring 33 will act to close it and hold it in closed position. Because the reservoir is symmetrical on both sides of the radial plane of the filling and discharge opening, having the two series of lugs or teeth 61 on opposite sides of the feet 62, no care need be exercised as to which side of the reservoir is adjacent the housing 10 when placed upon the door 30.

Having thus described my invention, what I claim is:

1. In liquid dispensing apparatus, the combination of a distributing receptacle, a supporting structure adjacent the same, a movable structure comprising a reservoir having an opening and adapted to be sustained by the supporting structure remote from said receptacle with said opening in elevated position and to be shifted laterally with a progressive end-over-end movement to an inverted position wherein said opening is in discharging relation to the distributing receptacle, said movable structure having a bearing part for cooperation with a part on the supporting structure, said parts having, on the one hand, voids and, on the other, projections arranged to enter said voids so as to render positive the coaction between the two parts.

2. In liquid dispensing apparatus, the combination of a distributing receptacle, a supporting structure adjacent the same, a movable structure comprising a reservoir having an opening and adapted to be sustained by said supporting structure remote from said receptacle with the opening in elevated position, the movable structure being adapted to be shifted laterally with a progressive end-over-end movement to an inverted position wherein said opening is in discharging relation to the distributing receptacle, and a track on the supporting structure, said movable structure being provided with a bearing part engaging the track, said bearing part and track having, on the one hand, voids, and on

the other, projections arranged to enter said voids thereby to render positive the coaction between said part and track.

3. In liquid dispensing apparatus, the combination of a distributing receptacle, a supporting structure adjacent the same, a movable structure comprising a reservoir having an opening and adapted to be sustained by said supporting structure remote from the receptacle with said opening in elevated position, the movable structure being adapted to be shifted laterally with a progressive end-over-end movement to an inverted position wherein said opening is in discharging relation to the distributing receptacle, and a track on the supporting structure, said movable structure including an arcuate bearing portion arranged for rolling contact with the track, said part and track having, on the one hand, voids and, on the other, projections that enter said voids.

4. In liquid dispensing apparatus, the combination of a distributing receptacle, a supporting structure adjacent the same, a movable structure comprising a reservoir having an opening and adapted to be sustained by said supporting structure remote from the receptacle with said opening in elevated position and to be shifted laterally with a progressive end-over-end movement to an inverted position wherein said opening is in discharging relation to said receptacle, opposed tracks on the supporting structure between which the movable structure travels, the movable structure including bearing parts for cooperation with the tracks, the tracks and bearing portions having, on the one hand, voids and, on the other, projections arranged to enter said voids.

5. In liquid dispensing apparatus, the combination of a distributing receptacle, a supporting structure, a movable structure comprising a reservoir having an opening and adapted to be sustained by the supporting structure remote from said receptacle with said opening in elevated position and to be shifted laterally to a position in operative relation to said receptacle, and a rack and pinion that coact, during such shifting of the movable structure, to positively invert the movable structure as it approaches the latter position thereby to dispose the aforesaid opening in discharging relation to said receptacle.

6. In a liquid dispensing apparatus, the combination of a distributing receptacle, a supporting structure adjacent the same, a movable structure comprising a reservoir having an opening and adapted to be sustained by the supporting structure remote from said receptacle with the opening in an elevated position and to be shifted laterally with an end-over-end movement to an inverted position wherein said opening is in discharging relation to the receptacle, a track on the supporting structure along which the second mentioned structure is movable, the movable structure having a laterally disposed arcuate bearing portion concentric to its axis of rotation and of a radius materially less than the radial distance from said axis to said opening for cooperation with said track thereby to effect inversion of the movable structure in a relatively short distance of travel.

7. In a liquid dispensing apparatus, the combination of a distributing receptacle, a supporting structure adjacent the same, a movable structure comprising a reservoir having an opening and adapted to be sustained by the supporting structure remote from the receptacle with said

opening in an elevated position and to be shifted laterally with a progressive end-over-end movement to an inverted position wherein said opening is in discharging relation to the receptacle, 5 opposed tracks on the supporting structure between which the second mentioned structure is movable, the movable structure having opposed arcuate bearing portions concentric to its axis of rotation and of a radius materially less than the radial distance from said axis to said opening for cooperation with said tracks thereby to effect inversion of the movable structure in a relatively short distance of travel.

8. In a liquid dispensing apparatus, the combination of a distributing receptacle, a supporting structure adjacent the same, a movable structure comprising a reservoir having an opening and adapted to be sustained by the supporting structure with the opening in an elevated position 10 and to be shifted laterally with a progressive end-over-end movement to an inverted position wherein said opening is in discharging relation to the receptacle, opposite tracks on the supporting structure between which the second mentioned structure is movable, the movable structure having laterally extended arcuate bearing parts for cooperation with said tracks, at least one of said tracks and the corresponding bearing part having, on the one hand, voids that are spaced apart and, on the other, projections that are adapted to enter said voids.

9. In liquid dispensing apparatus, the combination of a distributing receptacle, a supporting structure, a movable structure comprising a reservoir having an opening and adapted to be sustained by the supporting structure remote from said receptacle with said opening in an elevated position and to be shifted laterally with a progressive end-over-end movement to an inverted position wherein said opening is in discharging relation to the receptacle, opposed tracks on the supporting structure between which the second mentioned structure is movable, the movable structure having laterally extended arcuate bearing parts for cooperation with said tracks, the tracks and bearing parts having, on the one hand, voids that are spaced apart and, on the other, projections that are adapted to enter said voids.

10. In liquid dispensing apparatus, the combination of a distributing receptacle, a supporting structure, a movable structure comprising a reservoir having an opening and adapted to be sustained by the supporting structure remote from said reservoir with said opening in an elevated position and to be shifted laterally with a progressive end-over-end movement to an inverted position wherein said opening is in discharging relation to the receptacle, opposed tracks on the supporting structure between which the second mentioned structure is movable, said tracks having openings spaced apart longitudinally thereof, seats beyond the inner ends of the tracks, said movable structure having opposed rocker bearing parts for engagement with said tracks and teeth extending therefrom and arranged to enter said openings, the movable structure including feet spaced from said teeth for engagement with said seats when the movable structure is in inverted position.

11. In liquid dispensing apparatus, the combination of a distributing receptacle, a supporting structure, a movable structure comprising a reservoir having an opening and a base portion substantially diametrically opposite said opening

and adapted to be sustained by the supporting structure with said base portion resting thereon and in a location remote from said receptacle with said opening in elevated position, the movable structure being adapted to be shifted laterally with a progressive end-over-end movement to an inverted position wherein said opening is in discharging relation to said receptacle, said movable structure including an arcuate bearing portion in substantially concentric relation to its axis of rotation and of a radius considerably less than the radial distance between said axis and said opening, said bearing part being arranged to traverse a track-like part of the supporting structure thereby to effect the inversion of the movable structure in a relatively short distance of travel.

12. In apparatus of the class described, the combination of a housing having an open side and enclosing a reservoir compartment, a distributing receptacle at the bottom of said compartment, a door hinged to the housing adjacent the bottom of the open side thereof and which is adapted to be swung between a position in which it closes said open side and an approximately horizontal position, a reservoir having an opening and being adapted to be placed on said door when the latter is open with the aforesaid opening in elevated position, the reservoir having laterally extending parts including rocker bearing parts, rails extending inwardly from the open side of the housing in opposed relation to each other and wherewith the aforesaid bearing parts are arranged to engage with a rocking action as the reservoir is shifted laterally from the door with a progressive end-over-end movement to an inverted position with said opening in discharging relation to the distributing receptacle.

13. In apparatus of the class described, the combination of a housing having an open side and enclosing a reservoir compartment, a distributing receptacle at the bottom of said compartment, a door hinged to the housing adjacent the bottom of the open side thereof and which is adapted to be swung between a position in which it closes said open side and an approximately horizontal position, a reservoir having an opening and being adapted to be placed on said door when the latter is open with the aforesaid opening in elevated position, said reservoir having laterally extending portions including rocker bearing parts having teeth and terminating in feet, and tracks extending into the housing from adjacent the open side thereof in opposed relation to each other, said tracks having spaced openings for the reception of the aforesaid teeth when the bearing portions rock over the tracks, and depressed seats inwardly of the inner ends of the track wherewith said feet engage when the receptacle is in inverted position.

14. In apparatus of the class described, the combination of a housing having an open side, a door hinged to the housing on a substantially horizontal axis adjacent the bottom of said open side, stop means for arresting movement of the door when swung to an outwardly and slightly upwardly inclined position, spring means tending to close the door and serving to hold the door in closed position, the door's weight and its relation to said spring means being such as to cause the door to remain open in opposition to said means, glides on the door, a reservoir having a base and being adapted to be placed on the door with the base engaging the glides, the said reservoir having an opening opposite the base so that the

opening is in elevated position when the reservoir is on the door, the reservoir including laterally extending portions provided with arcuate bearing parts having spaced teeth and feet on said portions facing in substantially the same direction as the aforesaid opening, a basin supported within the housing in about the horizontal plane of the hinge connection between the door and housing, tracks extending inwardly from the open side of the housing in opposed relation to each other and over which the bearing portions of the reservoir are adapted to roll when the reservoir is shifted from the door into the housing with a progressive end-over-end action, the tracks having voids for the reception of the teeth of said bearing parts, and depressed seats inwardly of the tracks with which the aforesaid feet engage when the reservoir is in inverted position with the aforesaid opening in discharging relation to the distributing receptacle.

15. In a liquid fuel stove, the combination of a burner, a fuel basin, communicative connections between said basin and the burner, a support in juxtaposition to said basin, and an element comprising a reservoir having an opening adjacent its top and a rocker part arranged for rocking engagement with said support during movement of the reservoir along the support from an upright position remote from the basin to an inverted position in operative relation to the basin so that said opening may discharge into the same, the said rocker part being of a radius considerably less than the radial distance between the turning axis of the reservoir and said opening thereby to effect inversion of the reservoir in a relatively short distance of travel.

16. In a liquid fuel stove, the combination of a burner, a fuel basin, communicative connections between said basin and the burner, a support in juxtaposition to said basin, and an element comprising a reservoir having an opening adjacent its top and an arcuate bearing part arranged for rolling contact with said support during movement of the reservoir along the support from an upright position remote from the basin to an inverted position over the basin with said opening in discharging relation thereto, the said arcuate bearing part being of a radius less than the radial distance between the turning axis of the reservoir and said opening, the bearing part and support having, on the one hand, voids and, on the other, projections arranged to enter said voids.

17. In a liquid fuel stove, the combination of a burner, a fuel basin, communicative connections between the basin and burner, a support in juxtaposition to the basin, and an element comprising a reservoir having an opening adjacent its top and provided with an arcuate bearing portion arranged for rolling contact with the support in a movement of the element along the support from an upright position remote from the basin to an inverted position thereover with said opening in discharging relation to the basin, the bearing part and support having, on the one hand, voids and, on the other, projections arranged to enter said voids.

18. In a liquid fuel stove, the combination of a burner, a fuel basin, communicative connections between the burner and basin, a support in juxtaposition to the basin, and an element comprising a cylindrical reservoir having an opening adjacent its top and provided with a substantially circular bearing portion substantially concentric to the axis of the reservoir and of a radius con-

siderably less than that of the reservoir, the circular bearing portion including a foot in substantially radial alignment with said opening and a series of teeth spaced along the bearing portion on opposite sides of said foot, and a track along which the bearing portion is adapted to rock in a progressive end-over-end movement of the reservoir from an upright position remote from the basin to an inverted position thereover, said track having voids for the reception of certain of said teeth, and a seat beyond the inner end of the track whereon the foot rests when the reservoir is in inverted position.

19. In a liquid fuel stove, the combination of a burner, a fuel basin, communicative connections between the basin and burner, a reservoir support adjacent the basin, and a reservoir having an opening and adapted to be placed on said support with said opening elevated and, by a progressive end-over-end action, to be disposed in an inverted position over the basin with said opening in discharging relation thereto, the support and the portion of the reservoir engaging the same having, on the one hand, voids and, on the other, projections arranged to enter said voids.

20. In a liquid fuel stove, the combination of a burner, a fuel basin, communicative connections between the basin and burner, a support adjacent the basin, and a generally cylindrical reservoir having a base on its periphery and a discharge opening substantially diametrically opposite said base, said reservoir including an arcuate bearing portion substantially concentric with the periphery of the reservoir adapted to be rolled along the support during movement of the reservoir from an upright position remote from the basin to an inverted position thereover with said opening in discharging relation thereto, the radius of the bearing portion being materially less than that of the reservoir so as to effect inversion of the reservoir in a relatively short distance of travel.

21. In a liquid fuel stove, the combination of a burner, a fuel basin, communicative connections between the basin and burner, a support adjacent the basin, and a generally cylindrical reservoir having a base on its periphery and a discharge opening substantially diametrically opposite said base, said reservoir including an arcuate bearing portion substantially concentric with the periphery of the reservoir adapted to be rolled along the support during movement of the reservoir from an upright position remote from the basin to an inverted position thereover with said opening in discharging relation thereto, the radius of the bearing portion being materially less than that of the reservoir, the support having spaced voids so as to constitute thereof a rack, and the arcuate bearing portion of the reservoir having diametrically opposed series of teeth, the teeth of either of which series is adapted for interengagement with the support.

22. In a liquid fuel stove, the combination of a burner, a fuel basin, communicative connections between the basin and burner, a substantially horizontal support adjacent the basin, having voids spaced apart longitudinally thereof, and a cylindrical reservoir having a peripheral discharge opening and provided with a rocker portion for cooperation with said support, said rocker portion having projections arranged to enter the voids of the support.

23. In a liquid fuel stove, the combination of a burner, a fuel basin, communicative connections between the basin and burner, a substantially horizontal support adjacent the basin, having voids spaced apart longitudinally thereof, and a cylindrical reservoir having a peripheral discharge opening and provided with a rocker portion of a radius less than that of the reservoir for cooperation with said support, said rocker portion having projections arranged to enter the voids of the support.

MARC RESEK.
